PRESSER DEVICE FOR TACKING MACHINES

Michael McCann, Elizabeth, N. J., assignor to The
Singer Manufacturing Company, Elizabeth,
N. J., a corporation of New Jersey

Application July 23, 1943, Serial No. 495,865

7 Claims. (Cl. 112—235)

This invention relates to presser-devices for tacking machines and it has as an object to improve the presser-device disclosed in United States patent to Becker, No. 1,350,290, August 24, 1920.

Stated more specifically, this invention has as an object to provide an improved and simplified presser-device particularly adapted for holding the bows of hats while they are being attached to the hats by a conventional tacking machine.

These and other objects have been attained by the provision of a presser-device adapted to be carried directly by the conventional vertically shiftable presser-bar mounted in the bracket-arm head of a tacking machine and including two work-pressing elements rigidly and permanently secured together and swingable, as a unit, into and out of operative position.

In the present improved device the work-pressing elements are adapted to have a slight free swinging movement about their fixed pivots to permit them to move back and forth with the work while the work is shifted relative to the stitch-forming mechanism to produce the tack.

Also in the present construction the presser-devices are normally spring biased to a retracted position to facilitate insertion and proper positioning of the needle in its socket in the needle-bar, and a manually releasable latch member is provided to maintain the presser-devices in their effective or operative position during the tacking operation.

A drawing illustrating a preferred embodiment of this invention has been annexed as a part of this disclosure and in such drawing—

Fig. 1 is a side elevation of a tacking machine equipped with the present improved presser-device.

Fig. 2 is an enlarged front view of the presser-device, showing it attached to a conventional spring-depressed presser-bar and illustrating its normal position relative to the needle and needle-bar.

Fig. 3 is a side view of the presser-device shown in Fig. 2, illustrating, in dot-dash lines, the swinging movement of the presser-members under the influence of the work-shifting means and, in dotted lines, the presser-members swung to their retracted position.

Fig. 4 is a disassembled perspective view of parts of the improved presser-device, showing the main supporting bracket thereof attached to a presser-bar.

Referring more specifically to the drawing, the invention is disclosed as embodied in a tacking

machine comprising a base 1, standard 2, overhanging bracket-arm 3 and bracket-arm head 4, the latter carrying the usual reciprocating needle-bar 5 and spring-depressed presser bar 6. At its lower end the needle-bar carries an eye-pointed needle 7 (Fig. 2) which cooperates with a conventional rotary chain stitch looper 8 in the formation of stitches. Power to operate the machine enters the machine through a belt, not shown, adapted to engage loose and fast pulleys 9 and 10, respectively, on the rear end of a main shaft 11 journaled lengthwise of the arm 3. The forward end of the main shaft is connected, through conventional means, not shown, to reciprocate the needle-bar 5.

The rotary chain-stitch looper 8 is carried by the forward end of a rotary looper-shaft 12 journaled lengthwise in a work-supporting arm 13 forming a part of the bed 1. The looper shaft 12 is rotated from the main shaft 11 at a 1-to-1 ratio through the medium of a first pair of bevel gears 14, 15, a vertical shaft 16, journaled in the standard 2 and a second pair of bevel gears 17, 18.

Journaled horizontally in the standard 2 is a cross-shaft 19 to which is secured a clamp-actuating and cycle-control cam-wheel 20. This shaft is driven from the main shaft 11, at a reduced speed, by a worm 21 and worm-wheel 22 as is common in this type of sewing machine.

Slidably mounted on the upper surface of the work-supporting arm 13 is an endwise reciprocable work-plate 23 having, at its forward end, a serrated work-supporting portion 24 adapted to underlie and reciprocate the work relative to the stitch-forming mechanism. A work-guide or gauge 25 is carried by the work-plate and serves to locate the work relative to the stitching point.

Endwise reciprocations are given to the work-plate 23 from a cam-groove 26 formed on the inner face of cam wheel 20, through the medium of a two-armed lever 27 journaled, at 28, on a bracket 29 secured to the base 1. The upper arm 27^a of the lever 27 carries a roller 30 which tracks the cam groove 26 while the lower arm 27^b thereof is channeled and embraces a swivel-block 31 adjustably mounted on a stud 32 secured to and projecting upwardly from the work-plate 23. Thus rotation of the cam-wheel 20 causes the work-plate, and the work carried thereby, to be reciprocated back and forth lengthwise of the arm 13 during operation of the stitch-forming mechanism and in timed relation therewith to cause the stitch-forming mechanism to form a group of tacking stitches. The length of the tack 55 is determined by the setting of the swivel-block

31 in the channel of the lever-arm 27^b. After a predetermined number of tacking stitches have been made the machine is automatically brought to rest by a stop-motion mechanism, designated generally as 8, which, in turn, is controlled by the cycle-control cam-wheel 20.

Cooperating with the serrated portion 24 of the work-plate in holding the work, is the improved presser-device which comprises a main supporting bracket 33, secured to the lower end of presser-bar 6 by screw 34. This bracket has depending and laterally spaced ears 35 and 36, connected together by a cross-bar 33^a, between which is pivotally mounted, on screws 37 and 38, a work-pressing member 39. This member comprises spaced work-engaging elements 40, 41 connected together at their upper ends by a bridge portion 42. The elements 40, 41 have, at their lower ends, spaced and outwardly flared foot-portions 40^a and 41^a, respectively, between which the needle reciprocates. The pivot screws 37, 38 pass freely through apertures 35^a and 36^a in the ears 35 and 36, respectively, and are threaded into apertures 39^a in the member 39.

A coil spring 43 surrounds the shank of the screw 38 and has two outwardly projecting legs 43^a, 43^b of which one engages behind the element 41 while the other engages behind the cross-bar 33^a of the bracket 33, between the ears 35 and 36. The tension of spring 43 normally tends to turn the member 39 clockwise (as seen in Figs. 1 and 3) about its pivots 37, 38 to the position indicated in dotted lines in Fig. 3, in which position upwardly extending lugs 40^b and 41^b on the elements 40, 41, respectively bear against the inner face of the cross-bar 33^a, as shown in dotted lines in Fig. 3. This tendency of the member 39 to turn about its pivots is resisted by a manually releasable latch mechanism now to be described.

Slidably mounted in an aperture 44 in the ear 36 is a spring-pressed plunger 45, the free inner end of which is adapted to enter a somewhat larger opening 46 in the element 41. The plunger is normally pressed inwardly by a leaf-spring 47 secured, by hook portion 47^a and screw 48, upon the ear 36 and having, in its lower portion, a keyhole shaped slot 47^b in the smaller lower end of which is fitted a reduced neck portion of the plunger 45. The outer end of the plunger is knurled, as at 49, to provide a finger-grasp by means of which the plunger may be drawn outwardly, in opposition to the leaf-spring 47, to withdraw the free inner end from the aperture 46. When this is accomplished, the work-pressing member is swung upwardly about its pivot to the retracted position shown in dotted lines in Fig. 3, as hereinbefore described. In this retracted position the free end of the plunger 45 bears against the side of the work-engaging element 41 and remains ready to snap into the opening 46 when the presser-member is again swung downwardly into operative position. The diameter of the opening 46 is somewhat greater than the diameter of the end of the plunger which projects thereinto. Thus the member 39 is permitted to have a limited swinging movement about its pivots as the work-plate 23 and the work thereon are reciprocated lengthwise of the arm 13 and therefore, during the tacking operation, there is no relative movement between the work and the foot-portions 40^a and 41^a of the presser-members 40 and 41.

As above stated, the presser-device is carried by the lower end of the spring-depressed presser-

bar 6. This bar may be raised, in opposition to its depressing spring (not shown), to permit placing of the work on the work-plate and beneath the presser device, by manual actuation of a lever 50 fulcrumed at 51 on a bracket 52 secured upon the arm 3. One end of the lever 50 is forked and engages beneath a collar 53 secured upon the presser-bar. The opposite end of the lever may be connected to any suitable treadle or lever mechanism (not shown) as, for example, through the medium of a pull rod 54 indicated partially in Fig. 1.

Having thus set forth the nature of the invention, what I claim herein is:

1. In a sewing machine, stitch-forming mechanism, a horizontally reciprocable work-support, a vertically shiftable presser-bar, and a work-pressing device carried by said presser-bar, said work-pressing device comprising a bracket secured to said presser-bar, a plurality of vertically disposed work-engaging elements pivotally mounted on said bracket, spring means urging said elements in one direction about their pivots, and a stop for limiting the movement of said elements under the influence of said spring means, said work-engaging elements being adapted to be shifted in the opposite direction, in opposition to said spring means, by the movement of the work on said work-support.

2. In a sewing-machine, stitch-forming mechanism including a vertically reciprocable needle, a horizontally reciprocable work-support, a presser-bar, and a work-pressing device including a bracket carried by said presser-bar and a pair of work-engaging elements pivotally mounted on said bracket at opposite sides of said needle and shiftable by the work held on said work-support.

3. A presser-device for sewing machines comprising a presser-bar, a supporting bracket carried thereby, a pair of work-engaging elements pivoted on said bracket, spring means for shifting said work-engaging elements from an operative position to a retracted position, and latch means acting in opposition to said spring means to maintain said elements in operative position.

4. A presser-device for sewing machines comprising a supporting bracket having a pair of spaced vertically disposed ears, a work-pressing member pivoted between said ears and including a pair of work-engaging elements, spring means for swinging said work-pressing member about its pivot to position said elements in a retracted position, and a manually-releasable latch means carried by said bracket and engaging said member and acting in opposition to said spring means normally to maintain said work-engaging elements in operative position.

5. A presser-device for sewing machines having a reciprocating work-support, comprising a supporting bracket, a pair of work-engaging elements pivoted on said bracket, one of said elements being provided with an aperture, spring means tending to shift said work-engaging elements out of operative position, and a spring-pressed plunger carried by said bracket and having one end entering said aperture to maintain said elements in operative position in opposition to said spring means, there being sufficient play between the walls of said aperture and the portion of the plunger therein to permit said elements to be shifted back and forth with a work-piece on the reciprocating work-support.

6. A presser-device for a sewing machine hav-

ing a reciprocable work-holder, a presser-bar and stitch-forming mechanism including a reciprocating needle, comprising a bracket secured upon said presser-bar, a pair of work-engaging elements pivoted on said bracket, spring means for shifting said work-engaging elements to a retracted position, latch means acting in opposition to said spring means to maintain said elements in operative position in contact with a work-piece on said work-holder, and a lost-motion connection 10 between said work-engaging elements and said latch means to permit said members to oscillate as said work-holder and work-piece are reciprocated.

7. A presser-device for a sewing machine having a reciprocable work-holder, a presser-bar, and stitch-forming mechanism including a reciprocat-

ing needle, comprising a bracket secured upon said presser-bar, a unitary work-pressing member pivoted on said bracket and including spaced but integrally connected work-engaging elements, 5 one of which is provided with an aperture, spring means for shifting said work-pressing member to a retracted position, manually releasable latch means including a spring-pressed plunger having one end entering said aperture to maintain said elements in operative position in contact with a work-piece on said work-holder, the diameter of said aperture being materially larger than the diameter of the end of the plunger therein thereby permitting said work-engaging elements to oscillate as said work-holder and work-piece are reciprocated.

MICHAEL McCANN.
